UNITED STATES PATENT OFFICE.

ALEX BERNSTEIN, OF BOSTON, MASSACHUSETTS, ASSIGNOR TO THE BERNSTEIN ELECTRIC LIGHT MANUFACTURING COMPANY, OF SAME PLACE.

AUTOMATIC CUT-OUT FOR ELECTRIC LIGHTS.

SPECIFICATION forming part of Letters Patent No. 283,748, dated August 28, 1883.

Application filed February 26, 1883. (No model.)

To all whom it may concern:

Be it known that I, ALEX BERNSTEIN, of Boston, in the county of Suffolk and State of Massachusetts, have invented certain Improvements in Automatic Cut-Outs for Electric Lights, of which the following is a specification.

My invention relates to the application of electricity to the purposes of furnishing illumination or power, or to the employment of the same force in any other art in which the useful effect is obtained through the instrumentalities of some device acted upon by electricity developed at a comparatively distant point and supplied to the said translating device or instrument by means of suitable conducting-wires. The instrument or device to be actuated may be an electric lamp, an electromotor, a signaling-instrument, or any other instrument adapted to be operated in such a system; but to avoid prolixity I shall herein refer more particularly to electric lamps, especially as my invention is peculiarly an essential feature in systems of electrical illumination. In those systems in which a number of lamps or other centers of electrical work are employed in series it is obvious that an automatically-operating cut-out or short-circuiting device attached to each of the lamps is absolutely essential in order to prevent the circuit from being broken and the consequent failure, extinguishment, or cessation of operation of all the lamps included therein in case any one of the lamps should become defective or fail to conduct the current. Moreover, it is most desirable that the cut-out should be brought into operation before the passage of the current is entirely interrupted. In case lamps of the type invented by me and described in Letters Patent granted to me therefor January 30, 1883, No. 271,302, are used, it is possible that disintegration of the carbon and arcking resulting therefrom may occur by reason of some defect in the carbon or in the glass bulb inclosing the same, and consequent leakage. In such a contingency the lamp presents an abnormally high resistance to the passage of the current, the current is proportionally diminished in strength, and the other lamps in the same series commence to give less light. This result takes place before the faulty lamp becomes actually disabled, and it is of course desirable to short-circuit the

same immediately. This has heretofore been accomplished by arranging parallel to the lamp-circuit a normally-closed shunt-circuit, through which a portion of the current continually passes, and within which is included a short-circuiting device, adapted to become operative when an increased proportion of the electric current is diverted through the shunt-circuit in consequence of an increased electrical resistance offered by the lamp. To obtain the desired end I make use of an arrangement generally known as the "Wheatstone bridge or balance." This arrangement is in general use in connection with a galvanometer as a means of obtaining correct electrical measurements, and has also been extensively used in duplex telegraphy. That its adaptation to my purpose may be fully understood, I will briefly recapitulate the principles of operation, and inasmuch as in such recapitulation it will be convenient to refer to the drawings which accompany and illustrate this specification, I will first mention the characteristic features of the different figures in the said drawings.

Figure 1 is a diagram of the ordinary theoretical arrangement of the Wheatstone bridge, showing its combination with a cut-out device for the purpose which I have hereinbefore indicated. Fig. 2 is a similar diagram, showing a modification of the connections of the short-circuiting device. Fig. 3 shows one of the many practical forms of embodying in a compact form the required arrangement of circuits, resistances, and electro-magnetic appliances; and Fig. 4 is a detail thereof, showing a mechanical device whereby the cut-out, after being once brought into operation, is retained in an effective position.

It is of course not necessary in a Wheatstone bridge that the wires should be arranged in the parallelogrammatic form shown, nor in fact is it often done; but as the principle is more easily referred to and understood when thus arranged, it is usual to adopt that form. When the four wires composing the parallelogram 2, 6, 4, and 10 are of exactly equal resistance, and by means of main conductors 1 and 8, attached to the points *a* and *g*, a current of electricity is passed through the system from *a* to *g*, the said current will divide at *a*, half of it going through 2 and 6 and the other half through 4 and 10 to point *g*, and thence out by the main wire 8; but

any electro-magnetic instrument placed in circuit on a wire connected across from *f* to *b* will not be affected at all, and no current will pass along the cross-wire as long as 2, 6, 4, and 10 5 are of equal resistance. Again, when 2 bears the same proportion to 6 that 4 does to 10, no current will pass from *f* to *b* through the electro-magnet *M*; but if that proportion is destroyed a current at once flows through the 10 cross-wire, and any instrument included in circuit therewith is brought into action.

I arrange the lamp in circuit in one of the arms of the system and an electro-magnetic apparatus in the cross-wire or bridge, the latter being electrically disposed in accordance with the principles hereinbefore enunciated, so that no current flows through the coils of the cut-out actuating device so long as the lamp offers its proper and normal resistance.

20 If, however, from any cause, as explained above, the resistance of the lamp becomes abnormal and the lamp is in danger of being extinguished, the equilibrium of the bridge system will be disturbed and the cut-out becomes operative. In Fig. 1 the arrangement is shown theoretically. The incoming main-circuit wire is shown at 1, and, reaching the point *a*, divides itself into two branches, one leading from the point *a* by wire 2, resistance *R*, point *f*, resistance *R'*, and wire 6 to the point *g*, the other leading from point *a* by wire 4, lamp *l*, point *b*, wire 10, and resistance *R*² to the point *g*. At this point *g* the branch circuits reunite and pass out by the wire 8. From the point *f*, at the junction of the branches 2 and 6, to the opposite point, *b*, at the junction of the branches 4 and 10, extends a cross-circuit or bridge, composed of the wires 5 and 9 and the electro-magnet *M*, 40 through the coils of which the said cross-circuit passes. From the point *a* a wire, 3, leads to fixed contact *c*, and from the point *g* another wire, 7, leads to the armature-lever *d* of the bridge-wire electro-magnet *M*, this lever being suitably pivoted and normally retracted from the electro-magnet core *j*, owing to the non-magnetic condition of the core and to the retractile power of the spiral spring *e*. A limit-screw, *h*, prevents the lever from being 45 retracted too far. As shown in the figure, the armature-lever *d* is at its free end adapted to make contact with the fixed contact-point *c*, but normally does not make such contact, owing to the hereinbefore-described retractile devices. If from any cause the core *j* of the 55 bridge-magnet *M* should become energized, it is evident that the lever *d* would be thereto attracted, and that its free end would make contact with the point *c*, thus establishing a short circuit between the points *a* and *g*. In the figure the current is represented as proceeding in the direction of the arrows. Entering the system at *a*, and going out at *g* between those points, the current necessarily divides itself at the former point and traverses both circuits, the amount of current passing through each being inversely proportional to

their respective resistances. The lamp *l*, which we will suppose to have a resistance of four ohms, is included in the branch 4 between *a* and *b*. The branch 10 includes, between *b* and *g*, a resistance of one twenty-fifth ($\frac{1}{25}$) of an ohm; branch 2, between *a* and *f*, contains a resistance of four hundred ohms, and branch 6, between *f* and *g*, a resistance of four ohms. In this case, and as long as the lamp is in good order, no current will flow in the bridge-wire, and the electro-magnet contained therein remains inert, and the cut-out circuit consequently remains open, because the proper proportion between the branches being maintained the system is in equilibrium; but as soon as any defect occurs in the lamps, by which its resistance is increased or its integrity impaired, a current will commence to flow in the bridge-wire 5 between *f* and *b*, producing a magnetic effect in the core *j* of the electro-magnet *M*, which then actuates the cut-out by attracting the armature-lever. When the contact at *c* is thus made, a line of 90 very low resistance is established between *a* and *g*, and the greater portion of the current traverses the same. This device therefore prevents the integrity of the circuit from being dependent upon the individual perfection of each and every lamp in the series, as it would otherwise be.

There are many ways in which the principles underlying my invention may be embodied in a practical form. One of these is shown in Fig. 3, wherein the principal features of the cut-out apparatus are put together in a compact and condensed form.

A represents in section a case or box in which the working parts are inclosed. In the center thereof I place the electro-magnet *M* of the bridge-wire, which is provided with a soft-iron core, *j*, this being capable of adjustment, if necessary, by means of the screw *r* and lock-nut *q* at the rear. A spring-lever, *d*, is fastened to a screw, *s*, and is provided with an armature, *k*, by which it is drawn forward when the core *j* is magnetized. At other times it is retracted either by its own resiliency or by a suitable retractile, which is not shown. In the present case the inherent resiliency of the form of lever shown is sufficient. The free end of this lever has a contact-piece, *x*, which, when the armature is attracted, is brought against the fixed contact-point *c*, closing the short circuit. This fixed contact is supported by a metal bracket, *7*, which depends from and is in electrical connection with the screw-post *g*. The screw-posts *a* and *g* are terminals of the system.

Surrounding the electro-magnet *M*, and separated therefrom by an air-space, is a resistance-coil, *R*, and on the end of this coil is another and smaller coil, *R'*. The only objects of arranging the resistance-coils in this form are the convenience and compactness so obtained, no special electrical effect being either intended or desired. A sliding spindle, *p*, slides through a small hole in one corner of

the apparatus, and at its lower extremity is shouldered. This spindle is guided and kept in place by passing through the bracket-block o . The shouldered portion m of the spindle 5 end rests on the free end of the armature-lever, and the lower part, h , serves as a back limit for the armature-lever d . This portion of the apparatus is more clearly shown in Fig. 4, in which the external case, A , and the devices attached thereto are in section. The 10 resistance-coils and electro-magnet are both inclosed in a surrounding case, B , from which the core j projects. As shown, the armature-lever is inert, and rests on its back limit, the 15 spindle end m being elevated and supported upon the extreme end of the same lever.

In Fig. 3 the lever is in its forward position, the points x and c being in contact, while the spindle end m , no longer supported by the end 20 of the lever, has fallen into the space between the back of the lever d and the flat surface of the bracket-block o , thus serving as a wedge, whereby the contacts are firmly maintained, although the actuating-magnet M may be demagnetized as soon as the short circuit through 25 the contacts is completed.

I will now trace the circuits through the apparatus shown in Fig. 3, and it will be seen that they correspond with the theoretical arrangement in Fig. 1. The line-circuit, coming in, is united to the terminal a . From there it divides, as indicated above, the line representing the upper circuit in the diagram passing by wire 2 to the large resistance-coil R , thence 30 to the point f and smaller resistance, R' , which is divided from the larger by the non-conducting partition i ; leaving R' by the wire 6, it passes then to the terminal g and out by wire 8. The wire representing the branches 4 and 40 10 in the diagram may be traced as follows: from the terminal a by wire 4 to the lamp l , thence to the point b , and by wire 10, through the small resistance R^2 , to the terminal g and out to wire 8.

45 The cross-wire or bridge circuit may be traced from the point f to the electro-magnet M , then by wire 9 to the opposite point, b . The short-circuit or cut-out wire is led from screw-post a by wire 3 to screw s , thence through the 50 armature-lever d and contacts c and x and arm 7 to terminal g . In practice all the wires would be placed inside the case; but I have shown them separate for greater clearness.

Instead of adopting the mechanical retaining device shown in Fig. 4, I may allow the armature k , when attracted, to come into absolute contact with the core j ; where, after the cessation of the cross-wire current, it may be held by residual magnetism.

60 The short-circuiting device may be so arranged as to cut out the whole of the bridge system and connect the points a and g direct, as hereinbefore described, and shown in Figs. 1 and 3, or it may be arranged to cut out only 65 a portion of the arrangement, as shown in Fig. 2, where the resistance R only can be short-circuited. It is sometimes very advantageous

to adopt this method, and in that case the resistance of four ohms between f and g is left in the circuit, instead of the resistance of the lamp. When this is done, it becomes, however, necessary to construct the said resistance in such a way as to be capable of conveying strong currents of electricity without detriment to the wire. Moreover, when this method is employed I am enabled to dispense with retaining devices whereby the contacts of the short-circuit or cut-out wire are kept together, inasmuch as the current, after passing through the said cut-out wire and arriving at the point f , will there divide between the resistance R' and the cross-wire 5. A large proportion of the current will take the latter route, passing through the wire 5 and the actuating-magnet M to point b , and thence by wire 10, resistance R^2 , to g and out. It is therefore clear that the electro-magnet will in this case retain its attractive power, and will not allow the armature-lever to fall back. No mechanical retainer therefore is necessary. The specific 90 resistances which I have named are of course not essential, but merely illustrative.

Any resistance will answer, so long as the proper proportions are preserved, and those in the branches 2, 6, and 10 are dependent on 95 that of the lamp.

I claim—

1. In a system of electrical illumination wherein the lamps are arranged in series, the combination, at each light center, of a main or 100 supply circuit, a Wheatstone bridge, an electric lamp in one of the arms of the bridge, resistances bearing a definite ratio to the said lamp and to one another in the other arms of the bridge, whereby equilibrium may normally 105 be maintained in the cross-wire, an electro-magnet in the cross-wire thereof, and a normally-open or incomplete short-circuiting or cut-out wire extending between the terminals of the bridge, controlled by the armature of 110 said electro-magnet and adapted to be closed by the same when the electro-magnet becomes energized, substantially as described.

2. The Wheatstone bridge or balance at each lighting center, in combination with an electric 115 lamp in one of the branches thereof, a short-circuiting apparatus, and an electro-magnetic actuating device therefor, substantially as described.

3. A cut-out apparatus for an electric 120 lamp, consisting of a Wheatstone bridge or balance having the lamp included in one of its branches and resistances bearing a definite ratio to the said lamp and to one another in the other branches, whereby equilibrium may 125 normally be maintained in the cross-wire, a normally-open short-circuit wire extending between the terminals of the bridge and adapted, when closed, to cut out all of the bridge resistances, and an actuating electro-magnet in 130 the cross-wire of the bridge, adapted by the attraction of its armature to close the normally-open short circuit and cut out the resistances, as described.

4. The combination, in an electric lighting apparatus, of an electric lamp placed in a branch of a Wheatstone bridge, a short-circuit therefor, an actuating electro-magnet 5 in the cross-wire of the bridge, adapted to become operative when the equilibrium of the bridge is disturbed by reason of the lamp becoming defective or offering an abnormal resistance, and thereupon to close the short circuit, and a retaining device whereby the short circuit, when once made, is maintained, substantially as described.

5. An electric-light short-circuiting apparatus, consisting of the following instrumentalities: an electric lamp in one of the branches of a Wheatstone bridge, resistances bearing a definite ratio to the said lamp and to one another in the other branches of the bridge for the purpose of normally maintaining equilibrium 10 in the cross-wire, an electro-magnet in the cross-wire, adapted upon any change in the resistance of the several branches of the bridge to become operative, and a short-circuiting line extending from the entering terminal of 15 the bridge to one of the cross-wire junctions, adapted to be brought into action by the electro-magnet and to shunt the lamp and the greatest branch resistance, but to leave the cross-wire and electro-magnet in a branch circuit, whereby a portion of the current is diverted 20 continuously through the said electro-magnet after the establishment of the short circuit, thus retaining the said short circuit closed after it is once established, substantially 25 as described.

6. In an electric lighting system, the combination of an electric lamp and an automatic short-circuiting device therefor, the said lamp being connected in one of the arms of a Wheatstone bridge, which has an electro-magnet included in its cross-wire, and which, when the lamp is in its normal condition, is in equilibrium, and the said short-circuiting device being adapted to be actuated by the cross-wire 40 electro-magnet and to short-circuit the lamp when the equilibrium of the bridge is disturbed by reason of any change in the electrical resistance of the lamp.

7. The combination, with an electric lighting circuit and a lamp at any station thereof, of a Wheatstone bridge having the lamp in one of its branches and resistances in its other branches, one of the said resistances bearing a definite ratio to the lamp and the others a like ratio to 50 one another, an electro-magnet in the cross-wire of the bridge, normally inoperative but adapted to become operative on any change in the resistance of the lamp, and a normally-open short circuit connected with one of the 55 terminals of the bridge and with one of the cross-wire junctions, and actuated by the said electro-magnet when the equilibrium of the bridge is disturbed to shunt the lamp and a portion only of the other resistances, substantially as described.

8. A translating device and a resistance bearing a definite proportion thereto in cir-

cuit between two main-line terminals, in combination with a constantly-closed parallel circuit, which includes two other resistances, one 70 of which bears the same ratio to the translating device that the other bears to the fixed resistance in the circuit with the said translating device, the said parallel circuit being connected at its ends with the main-line terminals of the 75 lamp-circuit, a cross-wire, comprising an electro-magnetic helix, united to both wires and extending from a point in one of the circuits to a point proportionately corresponding in electrical resistance thereto in the other, and 80 a normally-open short circuit of very low resistance extending also between the main-line terminals and adapted to be closed or made continuous by the energization of the cross-wire magnet upon any change in any of the 85 four resistances, substantially as set forth.

9. The combination, substantially as herein-before described, of a main electric lighting circuit, a series of electric lamps disposed serially in the said circuit, and an automatic 90 cut-out for each lamp, consisting of an electro-magnet placed in the cross-wire of a Wheatstone bridge which includes the lamp in one of its branches and resistances bearing a definite ratio to the said lamp and to one another in its other 95 branches, whereby equilibrium may normally be maintained in the cross-wire, the said electro-magnet being adapted to remain inert so long as the resistance of the lamp remains normal, but to become operative when the equilibrium of the bridge is disturbed by any 100 change in the resistance of the lamp, and a normally-open short circuit round the lamp, and also round the other bridge-resistances, adapted to be actuated by the electro-magnet 105 in the cross-wire when the said magnet becomes operative, whereby the lamp and the other resistances may be short-circuited, for the purposes specified.

10. The combination, with an electric lamp, 110 of the electro-magnet M, the high resistance R, and the resistance R', bearing a definite ratio thereto, surrounding the electro-magnet, the armature-lever d, and bracket 7, forming part of a normally-open short circuit, and the sliding spindle p, the said electro-magnet being 115 normally neutral, but adapted to become energized and to bring its armature into contact with the bracket 7, when the lamp shall offer an abnormally-high resistance to the passage of 120 the current, and the said sliding spindle being constructed and adapted to fall between the armature-lever and the back limit thereof on the advance of the former, whereby the said armature-lever, after being once drawn forward, is retained in contact with the bracket, 125 substantially as and for the purposes described.

In testimony whereof I have signed my name to this specification, in the presence of two subscribing witnesses, this 21st day of February, 130 1883.

Witnesses: ALEX BERNSTEIN.
